UNITED STATES PATENT OFFICE.

WILLIAM O. HARRISON AND GEORGE W. JOHNSON, OF BUFFALO, NEW YORK.

DESIGN FOR A COMBINED VENDING AND DISPLAY CASE.

Application filed September 6, 1927. Serial No. 23,298. Term of patent 3½ years.

To all whom it may concern:

Be it known that we, WILLIAM O. HARRISON and GEORGE W. JOHNSON, citizens of the United States, residing at Buffalo, in the county of Erie and State of New York, have invented a new, original, and ornamental Design for a Combined Vending and Display Case, of which the following is a specification, reference being had to the accompanying drawing, forming a part thereof.

In the accompanying drawing the figure is a perspective view of a combined vending and display case showing our new design.

We claim:

The ornamental design for a combined vending and display case as shown.

WILLIAM O. HARRISON.
GEORGE W. JOHNSON.
